United States Patent Office

Des. 179,666
Patented Feb. 5, 1957

179,666

SPRAY GUN

Robert E. Sykes, Evanston, Ill., assignor to Bell & Gossett
Company, Morton Grove, Ill., a corporation of Illinois

Application December 14, 1954, Serial No. 33,557

Term of patent 14 years

(Cl. D62—2)

The figure is a perspective view of a spray gun embodying my new design. The side of the spray gun not illustrated is substantially like that shown.

I claim:

The ornamental design for a spray gun, as shown and described.
